UNITED STATES PATENT OFFICE

ROSCO O. PENCE, OF STERLING, KANSAS

BROODER STOVE AND HOVER

Application filed September 13, 1928. Serial No. 305,819.

This invention relates to brooder stoves and particularly to brooder stoves having a detachable hover which is shiftable so as to raise the hover or lower the hover under certain changes and conditions.

The general object of the invention is to improve certain details disclosed in my pending application Serial No. 193,836, filed on the 24th day of May, 1927, issued June 18, 1929, as Patent No. 1,717,851.

In that application I have shown a brooder stove which includes an ash pit, a combustion chamber, a magazine, and a smoke flue, the flue having a check draft damper and thermostatic means for coordinately controlling the action of the two dampers.

More specifically, one of the objects of the present invention is to provide a water chamber exterior to the magazine and between the ends of which the smoke flue passes, whereby to provide a means for supporting the hover in a vertically shiftable position and the water acting to retain a more uniform temperature within the brooder room and furnish moisture to the air in the brooder room, this water chamber further acting to restrain the dry heat ordinarily escaping from the magazine walls.

Another object is to so construct the stove that a space is left between the top of the combustion chamber and the lower end of the water chamber whereby the heat from the stove may be deflected outward beneath the hover.

Another object is to provide a removable outer wall for the smoke flue which permits the ready hanging of the check draft damper and the ready cleaning out of the smoke flue and adjacent parts.

A further object is to so construct the stove that it may be made up into sections and readily assembled and disassembled.

Another object is to provide improved means for adjustably supporting a hover upon the water chamber surrounding the magazine.

Other objects will appear in the course of the following description.

My invention is illustrated in the accompanying drawings wherein—

Figure 1 is a vertical sectional view through a brooder stove constructed in accordance with my invention;

Figure 2 is a section on the line 2—2 of Fig. 1;

Figure 3 is a section on the line 3—3 of Fig. 1;

Figure 4 is a face view of the detachable wall of the smoke flue;

Figure 5 is a fragmentary section of the water chamber of the brooder stove showing the connection of a drinking pan.

Referring to Fig. 1, it will be seen that the stove comprises the ash pit 10, the combustion chamber section 11, the grate 12, the supporting brackets 13 therefor, an upper section 14 for the combustion chamber, a lower magazine section 15 forming part of or carried by the section 14, and an upper magazine section 16 which carries upon it the water chamber 17 which is concentric to the section 16.

The section 11 is supported upon the top of the section 10 and the section 14 is supported upon the top of the section 11. The section 16 is supported upon the upper end of the lower wall section 15 of the magazine. The ash pit is provided with the air inlet opening 18 and the upper end of the magazine is normally closed by a cover 19. The water jacket or chamber 17 has a filling opening provided with a cover 20.

As will be seen from Fig. 2, the magazine is circular in cross section and surrounding the magazine is the water chamber 17. This extends nearly around the magazine but terminates in the vertical end walls 21 defining a smoke flue 22. This smoke flue extends down to the lower end of the magazine section 15 and this magazine section carries upon it the circularly extending baffle wall 23. The walls 21 terminate in spaced relation to this baffle wall so that an opening 24 is left through which the products of combustion passing upward from the combustion chamber 11 may pass through to the smoke chamber 22. The upper end of the smoke flues

is provided with a nipple 25 for the attachment of a smoke pipe.

The front wall of the smoke flue is con-

stituted by a removable plate 26 and by a wall 27 formed integral with the section 15 of the magazine and extending upward from the outer wall 11. The removable wall 26 5 has an aperture 26^a at its upper end on the inside of which is mounted a check draft damper 28. This check draft damper is detachably mounted upon pivots at its upper end upon the upper end of the inside face 10 of the wall 26 and has an outwardly projecting arm 29 to which the wire or rod 30 is connected.

The draft damper 31, pivoted at 32 by means of a plate 33, is attached to the wall 15 of the ash pit 10 and is provided with an outwardly projecting eye to which the lower end of the rod 30 is connected by a hook. This rod 30 is connected to a thermostat as will be later stated.

20 The outer face of the outer wall of the water chamber 17 is formed with a plurality of steps or ledges 34. It will be seen that the stove including this water chamber is preferably tapered upward.

25 The hover 35 is annular in form and provided with a ring 36, and the hover is preferably of sheet iron and its riveted or otherwise attached to this ring and the hover is preferably provided with a ventilator opening 37 having a damper 38. Adapted to fit upon the several steps 34, except the lower step of the series which is of sufficiently large diameter to engage with the ring 36, is a ring 39 which is cut away at 40 so as to fit 30 over the front wall 26 and is cut away at 41 to permit the passage of the wire or rod 30. The underface of this ring 39 is provided with the lugs 42 constituting brackets, as it were. When the hover is in its lowest 35 position, it rests upon the flange 43 at the base of the water chamber 17. If it is desired to elevate the hover, one of the rings 39 is placed upon the proper step 34 and the ring 36 forming an inner margin of the hover 40 is engaged with this ring 39.

45 It will be seen from Fig. 5, that the water chamber may be provided at its upper and lower ends with the outwardly extending circulating pipes 44 which may lead to a water heater whereby the drinking water for the chicks may be warmed. Any number of these drinking water heaters may be connected up with the water chamber 17.

50 With the construction which has been illustrated, the water jacket surrounding the magazine serves a three-fold purpose. Its outer surface provides a very simple means for supporting the hover in vertically adjusted position. The heated water within the water jacket or chamber 17 derives its heat from contact with the magazine walls and serves to secure or maintain a more uniform temperature in the brooder than is otherwise possible as it will remain hot for 55 a considerable time after becoming heated.

Furthermore, the slight amount of steam or vapor generated by this water heater, furnishes moisture to the air in the brooder, thus preventing this air from becoming too dry. This secures for the chicks a soft moist 70 heat instead of a dry harsh heat. The water within the water chamber becomes heated to the proper degree a short time after the stove is fired.

When the hover 35 is at its lowest position, the water jacket or water chamber 17 serves to restrain the dry heat otherwise escaping from the magazine walls. Under normal circumstances, the fuel within the magazine will tend to back-fire or heat up. 80 Considerable heat will be radiated outward from the walls of the magazine. This heat is modified therefore by the water contained within the water chamber 17. At the same time a certain amount of heat is radiated 85 from the space between the upper wall of the combustion chamber 14 and the lower wall of the water chamber 17. The cover or wall 26 of the combustion chamber is removable for the reason that it carries at its upper end 90 the check draft damper and as this damper is hinged on the inside it is necessary to have an opportunity to place the bearing surface of the damper. This can be easily done if this wall 26 is removable.

Furthermore, by making this wall 26 removable, it permits the smoke flue to be cleaned out. It will be seen that the cover or wall 26 engaging in the offset opening 40 of the ring 39, holds anyone of the rings 39 from 100 turning around the magazine. The hover, however, may be rotated upon this supporting ring 39 as desired.

I do not wish to be limited to any specific means for connecting or holding the sections together, but I have illustrated bolts 45 holding the section 11 onto section 10 and bolts 46 extending upward from the upper end of the section 11 to the flange 43 of the upper magazine section and water chamber. 110 Obviously these bolts might be arranged in a different manner without departing from the spirit of the invention.

The thermostat 47 is of any usual or suitable type, but I have illustrated this thermostat diagrammatically. It is mounted upon a bracket 48 and operates the arm 49 which is connected to rod 30. When the heat increases beyond a predetermined point the thermostat pushes the arm 49 down, which of course, closes the draft damper 31 and opens the check draft damper 28. When the heat decreases beyond a predetermined point, the thermostat moves in an opposite direction lifting the arm 49 and causing the opening of the draft damper and the closing of the check draft damper. I do not wish to be limited to this as I have stated before, to any particular construction of this thermostatic means.

As shown in Fig. 1, the rod 30 passes loosely through the eye on the draft damper 31 so that rod 30 may be raised and the check draft damper closed before the draft damper opens 5 and vice versa, the draft damper may close before the check draft damper opens.

What I claim is—

1. A brooder stove having a combustion chamber, a magazine smaller in diameter 10 than the combustion chamber, a water chamber partially surrounding the magazine and disposed on the exterior of the stove and forming a part of the outer wall thereof, the lower end of the water chamber being spaced 15 from the upper end of the combustion chamber to constitute a heat diffusing space opening to the exterior of the stove.

2. A brooder stove having a combustion chamber, a magazine smaller in diameter 20 than the combustion chamber and extending down into the combustion chamber below the top wall thereof, a water chamber partially surrounding the magazine, the end walls of 25 the water chamber forming the side walls of a smoke flue, the inner wall of which is formed by the wall of the magazine, and an outer wall for said smoke flue, the smoke flue being continued down into the upper portion 30 of the combustion chamber surrounding the lower end of the magazine.

3. A brooder stove having a combustion chamber, a magazine smaller in diameter than the combustion chamber and extending down into the combustion chamber below the 35 top wall thereof, a water chamber partially surrounding the magazine, the end walls of the water chamber forming the side walls of a smoke flue, the inner wall of which is formed by the wall of the magazine, and an 40 outer wall for said smoke flue, the smoke flue being continued down into the upper portion of the combustion chamber surrounding the lower end of the magazine, the lower end of the smoke flue being provided with a circumferentially extending baffle wall. 45

4. A brooder stove having a combustion chamber, a magazine smaller in diameter than the combustion chamber, and extending down into the combustion chamber below the 50 top wall thereof, a water chamber partially surrounding the magazine, the end walls of the water chamber forming the side walls of a smoke flue, the inner wall of which is formed by the wall of the magazine, and an 55 outer wall for said smoke flue, the smoke flue being continued down into the upper portion of the combustion chamber surrounding the lower end of the magazine, the outer wall of the smoke flue being detachable.

60 5. A brooder stove having a combustion chamber, a magazine smaller in diameter than the combustion chamber, and extending down into the combustion chamber below the top wall thereof, a water chamber partially 65 surrounding the magazine, the end walls of

the water chamber forming the side walls of a smoke flue, the inner wall of which is formed by the wall of the magazine, and an outer wall for said smoke flue, the smoke flue being continued down into the upper portion 70 of the combustion chamber surrounding the lower end of the magazine, the outer wall of the smoke flue being detachable, the upper end of the detachable outer wall having a damper opening, and the stove body below 75 the combustion chamber having an air inlet opening, a draft damper coacting therewith, a check draft damper pivoted upon the inside of the outer wall of the smoke flue and swinging inward, and a common connection 80 between the two dampers whereby they may be operated approximately simultaneously.

6. A brooder stove comprising a body having an ash pit, a grate, and a combustion chamber, the upper end of the body carrying a magazine section smaller in diameter than the combustion chamber and extending down thereinto, an upper section for the magazine resting upon the lower section, a water chamber partially surrounding the upper section 85 of the magazine and spaced from the upper end of the combustion chamber, the end walls of the water chamber constituting the side walls of a smoke flue extending down the full length of the magazine and opening into the combustion chamber, an outer wall for the smoke flue which is detachable and formed at its upper end with a check draft opening, an inwardly swinging check draft damper mounted upon the upper end of the outer wall 90 of the smoke flue, the ash pit having an air inlet opening, a damper therefor, and means common to both of said dampers for co-ordinately controlling both of said dampers 95 simultaneously.

7. A brooder stove having a combustion chamber and an upwardly tapering portion above the combustion chamber, the outer wall of said portion being stepped, a series of rings differing in diameter and adapted to fit upon 100 said steps, and a hover annular in form to fit upon and over anyone of said rings whereby the hover may be adjusted vertically with reference to the upper portion of the brooder stove. 110

8. A brooder stove having a combustion chamber, a magazine extending upward therefrom, a water heating chamber partially surrounding the magazine, and a smoke flue exterior to the magazine and disposed between 120 the end walls of the water chamber and having an outer wall, the exterior of the water chamber being formed with a series of shoulders decreasing in diameter upward, a series of rings adapted to fit on and rest upon said shoulders, and an annular hover, the inner margin of which is adapted to be supported on any one of said rings. 125

9. A brooder stove having a combustion chamber, a magazine extending upward there- 130

from, a water heating chamber partially surrounding the magazine, and a smoke flue exterior to the magazine and disposed between the end walls of the water chamber and having an outer wall, the exterior of the water chamber being formed of a series of shoulders decreasing in diameter upward, a series of rings adapted to fit on and rest upon said shoulders, and an annular hover, the inner margin of which is adapted to be supported on any one of said rings, the outer wall of the smoke chamber being detachable and projecting slightly beyond the outer face of the outer wall of the water chamber, each of said rings being cut away to accommodate the projection of the outer wall of the smoke chamber whereby the ring will hold the wall of the smoke chamber in place, and the projecting wall of the smoke chamber will prevent a rotation of the ring.

In testimony whereof I hereunto affix my signature.
